UNITED STATES PATENT OFFICE

CHARLES SHULMAN, OF NEW YORK, N. Y., ASSIGNOR TO APT NOVELTY COMPANY, INC.,
OF NEW YORK, N. Y.

DESIGN FOR A SMOKER'S STAND OR ARTICLE OF SIMILAR NATURE

Application filed August 9, 1930. Serial No. 36,616. Term of patent 7 years.

To all whom it may concern:

Be it known that I, CHARLES SHULMAN, a citizen of the United States, residing in New York, in the county of New York and State of New York, have invented a new, original, and ornamental Design for a Smoker's Stand, or Article of Similar Nature, of which the following is a specification, reference being had to the accompanying drawing, forming a part thereof.

The figure is a perspective view of a smoker's stand showing my new design. The parts shown in broken outlines involve mere repeats of the completed portions in solid outline.

The appearance shown in the present figure is substantially the same on the opposite side.

I claim:

The ornamental design for a smoker's stand, or article of similar nature, as shown and described.

In testimony whereof I affix my signature.

CHARLES SHULMAN.
